(57) **CLAIM**

The ornamental design for the hose clamp, as shown and described.

DESCRIPTION

FIG. 1 is a perspective view of the hose clamp showing my new design;

FIG. 2 is a rear view thereof;

FIG. 3 is a front view thereof;

FIG. 4 is a top plan view thereof;

FIG. 5 is a bottom plan view thereof;

FIG. 6 is a left side view thereof;

FIG. 7 is a right side view thereof; and,

FIG. 8 is a perspective view thereof in a state of use.

The broken lines shown in FIGS. 1-8 are included for the purpose of illustrating environment and form no part of the claimed design.
